United States Patent Office.

RALPH ADAMS, OF OTTAWA, ILLINOIS.

Letters Patent No. 73,277, dated January 14, 1868.

IMPROVEMENT IN GATES.

The Schedule referred to in these Letters Patent and making part of the same.

TO ALL WHOM IT MAY CONCERN:

Be it known that I, RALPH ADAMS, of Ottawa, in the county of La Salle, and State of Illinois, have invented a new and improved Gate; and I do hereby declare that the following is a full, clear, and exact description thereof, which will enable those skilled in the art to make and use the same, reference being had to the accompanying drawings forming part of this specification, in which—

Figure 1 is a plan view of my improved gate.

Figure 2 is a sectional elevation of the same through line $x x'$, fig. 1.

Figure 3 is a sectional elevation of the gate through the line $y y'$, fig. 1.

Similar letters of reference indicate corresponding parts.

This invention relates to an improved gate, which can be opened and closed by persons while on horseback or in vehicles.

A A A are the bottom framing, which supports the gate and its operative mechanism. B is the gate. C the post, to which it is partially hinged. D are the lever-posts, having pivoted thereto the levers L by screw-pivots α . A toothed rack, E, is connected by rods of iron, R, to the levers by pivots at γ . This rack works in a slot cut in the post C, near its bottom, and is moved horizontally to the right or left through the said slot, according as the levers L L, to which it is connected, are actuated to the right or left, and in so moving opens the gate, as will be now explained.

A half pinion, G, firmly attached to the bottom of the upright, F, of the gate-frame, has its teeth presented to and engaging with the rack above described, so that when the levers are pushed, the rods R draw or push the rack, which latter, engaged as aforesaid with the pinion G on the upright F, forming part of the gate, B, opens or closes the gate. A rope or cord, m, passes through eyes i on the levers and staples t, on the upright F, and thence downward and through the rear end n of the latch-bar P. This latch-bar is supported on a pivot, g, in the gate-frame, and the end, c, catches upward into a notched plate, k, attached to the post C', so that the rear end, n, of the latch-bar is to be raised to disengage the said bar from its notch in the plate k. A spring, S, bears down the end, n, of the bar, and thus keeps the gate latched until the cord m is drawn. This cord is not riven loosely through the end of latch-bar, as through the other eyes and staples, but is tied or otherwise prevented from rendering when it is drawn; it therefore lifts the end, n, which lowers the end, c. The lower pintle of the upright, F, is shown at q, having a step bearing in the plate u. The upper hinge consists of a pintle, b, working in a plate, d, which is bolted to the post C.

In operating this gate, it is only required to ride up within reach of one of the levers L, and drawing the cord m till the latch-bar is disengaged from its notch, and then push with the same hand the lever; the gate will then open from the person pushing. If the lever is pulled the gate will open toward the person pushing. A pawl, v, pivoted to one of the levers L, near its upper end, traverses on the arc of a segmental plate, j, having a notch, f, in which the said pawl catches when the gate opens. This pawl has an arm, by which it is pivoted to a small lever-handle, l, which latter is pivoted to the lever L, all as shown. One of these pawls, with its connections, is to be placed on each lever L, and as the one opposite to the person opening the gate is the one which catches after the gate has opened, so that when the rider or driver passes through he has only to liberate the pawl by pressing on the lever l, to shut the gate after he has passed through, the pawl on the lever he has left does not catch until the gate is opened toward it.

The advantages of my improved gate consist in the facility with which it is operated, its simplicity of construction, and small cost.

There are many gates provided with mechanism for being opened from a vehicle, but they are all more or less complicated, and generally get out of repair in a short time. My gate, having no complicated parts, is therefore not liable to become inoperative from ordinary wear, and will last for years.

I claim as new, and desire to secure by Letters Patent—

1. The levers L and rods R, in combination with the rack E, substantially as shown, for the purpose of opening a gate, all as set forth.
2. The latch-bar P and cord m, in combination with the levers L, substantially as shown and for the purpose specified.
3. The pawl v, in combination with the levers l and L, and notch f, for the purpose of holding a gate open, substantially as shown.

RALPH ADAMS.
